US00D957822S

(12) **United States Design Patent** (10) **Patent No.:** **US D957,822 S**
(45) **Date of Patent:** **** Jul. 19, 2022**

(54) **TOOTHBRUSH**(71) Applicant: **The Gillette Company LLC**, Boston, MA (US)(72) Inventors: **Uwe Jungnickel**, Koenigstein Taunus (DE); **Dominik Langhammer**, Frankfurt (DE)(73) Assignee: **The Gillette Company LLC**, Boston, MA (US)(**) Term: **15 Years**(21) Appl. No.: **29/752,903**(22) Filed: **Sep. 29, 2020****Related U.S. Application Data**

(62) Division of application No. 29/704,079, filed on Aug. 30, 2019, now Pat. No. Des. 901,183.

(30) **Foreign Application Priority Data**

Mar. 22, 2019 (WO) 970011959

(51) **LOC (13) Cl.** ..... **04-02**(52) **U.S. Cl.**USPC ..... **D4/101**(58) **Field of Classification Search**

USPC D4/100, 101, 102, 104, 105, 106, 107, D4/108, 109, 110, 111, 112, 113, 114, D4/115, 116, 119, 130, 132, 133, 134, D4/136, 137, 138, 199

CPC ... A46B 2200/1066; A46B 5/02; A61C 17/16; A61C 17/22

(57) **CLAIM**

The ornamental design for a toothbrush, as shown and described.

DESCRIPTION

FIG. 1 is a perspective view of a toothbrush;
FIG. 2 is a front elevation view thereof;
FIG. 3 is a right side elevation view thereof;
FIG. 4 is a rear elevation view thereof;
FIG. 5 is a left side elevation view thereof;
FIG. 6 is a top plan view thereof; and,
FIG. 7 is a bottom plan view thereof.
The broken lines illustrate environmental structure and form
no part of the claimed design.
